UNITED STATES PATENT OFFICE.

FRANK ALLEY, OF WEST HARTFORD, CONNECTICUT, ASSIGNOR TO THE ARROW ELECTRIC COMPANY, OF HARTFORD, CONNECTICUT, A CORPORATION OF CONNECTICUT.

SAFETY DEVICE FOR STAMPING-PRESSES AND THE LIKE.

1,384,654.

Specification of Letters Patent. Patented July 12, 1921.

Application filed January 4, 1921. Serial No. 434,978.

To all whom it may concern:

Be it known that I, FRANK ALLEY, a citizen of the United States, residing in West Hartford, in the county of Hartford, State 5 of Connecticut, have invented a certain new and useful Improvement in Safety Devices for Stamping-Presses and the like, of which the following is a specification.

My invention consists of an improved 10 safety device with a mechanically actuated lock for stamping presses and the like, to prevent the dies from injuring the hands of the operator of the machine.

My invention is applicable to any machine 15 where the operator alternately feeds work to the machine and causes the mechanism to operate, but it is more particularly applicable to stamping presses. I am aware that in stamping presses provided with safety devices, locking mechanisms have been combined therewith, but all such devices have been controlled by the actuating treadle. The safety shield has been so connected to 20 the actuating treadle of the presses that the plunger die cannot descend until the shield is 25 fully down between the operator and the dies. With such devices the release of the treadle releases the safety shield and the latter flies up, exposing the plunger die before the latter 30 has completed its downward movement.

This momentary exposure is the cause of accidents to the operator's hands. My invention consists of the provision of means whereby it is mechanically certain that the shield 35 will be held down in safety position until the plunger die has completed its downward movement and is about, or has begun, to rise again.

In the accompanying drawings, Figure 1 40 is a side elevation of a stamping press to which one form of my invention has been applied the shield being shown in its safety position;

Fig. 2 is a front elevation of part of the 45 press with the shield in its normal elevated inoperative position;

Fig. 3 is a horizontal section of the same press taken along line A A, Fig. 2;

Fig. 4 shows the details of part of my in- 50 vention;

Fig. 5 is a horizontal section similar to Fig. 3, showing a modified form of construc- 105 tion.

Fig. 6 is a modified form of construction of part of my invention.

I have indicated the frame of the press at 55 1, and the die bed at 2. On the die bed is bolted the die 3 and adjacent to the die bed is the operator's table 4. The moving or plunger die 5 is bolted in the "gate" or cross-head 6 to which a reciprocating motion can be imparted through the connecting rod 7 and the crankshaft 8 by the flywheel 10, when the clutch 9 is thrown in.

In a stamping press the flywheel is the 65 only part continuously in motion. To actuate the plunger die the operator must throw in the clutch 9 by means of a suitable lever such as treadle 11, operating through the medium of any suitable connections. The 70 treadle is shown pivoted to the frame of the press and has hinged to it the lower end of rod 12. The upper end of this rod actuates the safety device 13 which, in the construction shown, operates guard arms 14. These 75 guard arms carry a safety shield 15 which is adapted, when in the down or safety position, to prevent the operator putting or leaving his hands within range of the plunger die. This safety device is pivoted on shaft 80 16 and, owing to the spring 17, tends to return the safety shield 15 to the elevated position shown in Fig. 2.

To make certain that safety shield 15 remains down in the safety position until the 85 operation of the machine has passed beyond the danger point, I provide the latch 18 positioned to engage one guard arm 14. The latch is shown in detail in Fig. 4. It is pivoted to the head 19 of slide rod 20 by 90 pin 21. In the slide rod 20 is the recess 22 containing the compression spring 23 and sliding pin 24. This spring 23 presses the sliding pin 24 against latch 18 so as to tend to keep it in the path of movement of the 95 guard arm 14. When the guard comes down to safety position its carrying arm pushes the latch back and as soon as the guard arm passes the latch, the spring pushes the sliding pin 24 and the latch out again and the 100 guard arm is caught and held in safety position. The slide rod 20 is fastened to lever 25 by a rocking joint. The lever is pivoted at 26 and has attached to it between the rocking joint and the pivot point, 26, 105 one end of the tension spring 27. This

spring tends to keep the latch in engagement with the guard arm and also to keep the roller 28, on the upper end of the pivoted lever 25, bearing against cam 29. In 5 this way the latching means are controlled by a power-operated part of the press mechanism.

Since the cam 29 is mounted on the crank-shaft 8, it can be seen that the reciprocation of pivoted lever 25 and consequently 10 the withdrawal from and the return to engagement position with the guard arm of the latch 18 will operate in positive connection with the plunger die. The cam is so 15 set that the latch does not withdraw from the path of movement of the guard arm and allow the safety shield to be raised from safety position by spring 17 until the plunger die has operated on the work in die 3 20 and is withdrawing from contact therewith.

In Fig. 5 I show a slightly different form of construction. The guard arm is still pivoted on shaft 16 but is mounted outside the frame of the press and there is only one 25 arm, instead of two.

Fig. 6 illustrates a modified method of reciprocating the pivoted lever 25. Instead of depending on a tension spring to make the lever bear against the single cam 29, I 30 make the cam double and actuate it positively in both directions from the crank-shaft 8.

I do not wish to restrict myself to the details described, as they may be readily modified without departing from my invention. 35

I claim as my invention:

1. A safety device for stamping presses and the like, comprising a movable safety shield in combination with a movable latch 40 to lock the shield in safety position and independent means adapted to be continuously controlled by a power-operated part of the press mechanism for operating said latch.

2. A safety device for stamping presses

and the like, comprising a vertically movable safety shield in combination with a movable latch to lock the shield in safety position and independent means adapted to be continuously controlled by a power-operated part of the press mechanism for operating said latch. 45

3. A safety device for stamping presses and the like, comprising a movable safety shield, a catch to lock it in safety position, and rotary cam means controlled by the 55 power shaft of the press for releasing the shield at any desired point in the operation of the press.

4. A safety device for stamping presses and the like, comprising a movable safety 60 shield, a movable catch to lock the shield in safety position, and means controlled by a power operated part of the press mechanism for unlocking the shield only after the plunger die begins its return stroke. 65

5. A safety device for stamping presses and the like, comprising a movable safety shield, a movable catch to lock the shield in safety position, a slide rod adapted to reciprocate said catch out of and into locking position with the shield and rotary cam means controlled by a power operated part 70 of the press mechanism for actuating said slide rod.

6. A safety device for stamping presses 75 and the like, comprising a movable safety shield, a slide having a catch to lock the shield in safety position, means to reciprocate said slide and its catch out of and into locking position with the shield, said means 80 comprising a pivoted lever controlling said slide, a cam and a power-driven shaft causing said cam to reciprocate said pivoted lever.

In testimony whereof I have signed my 85 name to this specification.

FRANK ALLEY.
